Willis & Roys,

UNITED STATES PATENT OFFICE.

WILLIS E. ROYS, OF NEW YORK, N. Y.

AUTOMATIC STEAM-CONTROLLER.

No. 800,323.

Specification of Letters Patent.

Patented Sept. 26, 1905.

Application filed February 25, 1904. Serial No. 195,203.

To all whom it may concern:

Be it known that I, WILLIS E. ROYS, a citizen of the United States, and a resident of the city of New York, Richmond Hill, borough of Queens, in the county of Queens and State of New York, have invented a new and Improved Automatic Steam-Controller, of which the following is a full, clear, and exact description.

10 The invention relates to heating systems for buildings; and its object is to provide a new and improved heat-controller especially designed for use on radiators and arranged to automatically shut off the heating medium 15 in a room whenever the temperature thereof rises to a predetermined degree and in case the temperature falls below the predetermined degree to automatically turn on the heat to the room.

20 The invention consists of novel features and parts and combinations of the same, as will be more fully described hereinafter and then pointed out in the claims.

A practical embodiment of the invention 25 is represented in the accompanying drawings, forming a part of this specification, in which similar characters of reference indicate corresponding parts in all the views.

Figure 1 is a side elevation of the improvements as applied to a steam-radiator. Fig. 2 is a transverse section of the controller for the valve of the steam-inlet pipe of the radiator. Fig. 3 is a similar view of the controller for the water-outlet valve of the radiator, and Fig. 4 is a front view of the controller for the inlet-valve of the radiator.

In the invention presently to be described in detail use is made of the expansive force of a liquid capable of expanding under the 40 heat of the room and to such an extent that at a predetermined degree of heat in a room furnished by a heating system of this approved construction the heat for the room is shut off automatically until the temperature falls to the minimum degree of heat desired 45 in a room, so that each room in a building is subject to its own heat-controller, and consequently a uniform heating of the whole building takes place.

50 As shown in the drawings, the improvement is applied to a steam-heating system, and each radiator A of the system is of the usual construction provided with a steam-supply pipe B, containing a valve C, preferably in the form of a globe-valve and having the outer end of its valve-stem C' connected

to one end of a movable plate F, as plainly shown in Fig. 2. A member H is located exteriorly of the radiator, and its upper end is secured to the pipe B, as at I. The lower 60 ends of said plate F and member H are loosely connected together to permit the plate F to move angularly with reference to the member H. A thermostat A' is placed on the outer side of the plate F at the lower end thereof. 65 A plate S bears against the outer side of the thermostat and is held in contact therewith by means of screws E, the threaded stems of the latter engaging threaded openings with which the member H is provided. Hence by turning said screws the said plate S may be adjusted 70 so that the same may be caused to press against the thermostat with any desired degree of force. A spring D, which is here shown as a coil-spring, is placed between the upper portions of the plate F and member H and serves to force the said plate F outwardly.

Since the thermostat and its connections and supporting elements are disposed exteriorly of the radiator, the member H being 80 spaced from the radiator and the plate F being on the outer side of the member H and spaced therefrom, and the thermostat being on the outer side of the plate F, a free circulation of air is permitted between the radiator and the member H and between the latter and the plate F, so that the thermostat is controlled by the temperature of the room in which the radiator is located as distinguished 85 from the temperature of the radiator itself. 90

The action is as follows: When the temperature of the room rises, say, to 70° Fahrenheit, the liquid in the thermostat expands like mercury in a thermometer and causes the plate F to move inwardly and close the valve 95 C. When the temperature of the room falls below 70°, the liquid in the thermostat contracts, releasing the pressure on the plate F, and the spring D thereupon moves the said plate outwardly and causes the same to open 100 said valve. By appropriately turning the screws E the pressure of the spring D may be regulated and the thermostat set to operate to close the valve at any desired degree of heat.

In the steam-inlet pipe B is arranged the 105 usual cut-off valve K for turning off the steam from the radiator A whenever it is desired to do so.

The radiator A is provided on its water-discharge pipe B' with a thermostat to control the outflow of the water, and this thermostat is preferably of the construction shown

in Fig. 3 and contained in a chamber L, preferably disposed vertically and containing united metal bars N and N' of different expansibility and secured at their upper ends 5 to the upper end of the chamber L, the bar N carrying at its free end a valve O, adapted to be seated on the inner end of a discharge-plug P, held adjustably in the chamber L and opening into a return-pipe Q for carrying the 10 water of condensation back to the steam-boiler or other place. Now the steam from the radiator A, passing by way of the discharge-pipe B' into the chamber L, heats the bars N and N' therein, so that the valve O is 15 moved onto its seat on the plug P to close the latter, and thereby prevent escape of steam to the return-pipe Q. Now when the steam in the radiator and in the chamber L condenses and the water of condensation in filling 20 the chamber L reduces the temperature of the thermostat-bars N and N' then the said bars flex in an opposite direction, and consequently the valve O is moved off its seat on the plug P to allow the water of condensation 25 contained in the chamber L to flow out through the plug P and to pass into the return-pipe Q. When the steam again passes into the chamber L after the latter is drained of water, then the thermostatic bars N and N' 30 again cause the valve O to move to its seat on the plug P to close the latter.

In order to prevent undue vibration or fluctuation of the valve O, owing to the expansion and contraction of the thermostatic bars N 35 and N', additional united metal bars N² and N³ are provided, secured at one end to the bar N' and curved to press at their middle portion against the screw R of the chamber L and to press with their front end on the free 40 end of the bar N, so that when the auxiliary bars N² and N³ expand with the bars N and N', as previously described, then their free ends press against the bars N and N' to hold the valve O firmly to its seat, and thus prevent 45 undue vibration of the valve O and "hammering" of the valve in the water, as is so frequently the case with thermostats of this construction not provided with the auxiliary bars N² and N³.

The screw R is used to adjust the bars so 50 that proper expansion will be secured to just seat the valve O at 212° Fahrenheit.

Now from the foregoing it will be seen that the inlet of the steam to each radiator is controlled by a thermostat actuated by the expansive force of a liquid confined in a closed chamber and the discharge of the water from the radiator is controlled by a thermostat actuated by the steam and water of condensation of the radiator. 55

The device is very simple and durable in construction, can be cheaply manufactured and readily applied to radiators as now constructed, and it is also very evident that the device may be readily applied. 60

Having thus described my invention, I claim as new and desire to secure by Letters Patent—

1. In combination with a radiator having a supply-pipe and a controlling-valve therein, a member secured to the said supply-pipe and disposed exteriorly of and spaced from the radiator, a movable plate spaced from and disposed on the outer side of said member and connected to the valve to control the latter, a spring to normally open said valve, 70 and a thermostat on the outer side of the movable plate and adapted to operate the same to close said valve. 75

2. In combination with a radiator, a pipe communicating therewith and having a valve, a member secured to the said pipe and disposed exteriorly of the radiator, a plate movable toward and from said member, disposed on the outer side thereof and connected to the valve, a spring to move the movable plate in one direction and a thermostat also disposed exteriorly of the radiator, and spaced from the said member, said thermostat being effective to move the movable plate in the reverse direction. 80

In testimony whereof I have signed my name to this specification in the presence of two subscribing witnesses. 85

WILLIS E. ROYS.
